UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,106,950.

Specification of Letters Patent. Patented Aug. 11, 1914.

Application filed September 27, 1912. Serial No. 722,582.

To all whom it may concern:

Be it known that I, ALFRED G. F. KUROWSKI, a citizen of the United States, residing in Brooklyn borough, in the county of New York, city and State of New York, have invented certain new and useful Improvements in Type-Writing Machines, of which the following is a specification.

The present invention relates to typewriting machines, and especially to machines which have a tabulating mechanism, in which a series of stops on the typewriter carriage can be selectively moved into position, where they are intercepted by key-operated counter-stops and thereby arrest the typewriter carriage.

In the present instance, the invention is shown as applied to an Underwood typewriting machine in which there is an array of stops on the paper carriage, which may be normally in ineffective positions. When moved into effective positions, any one of said stops will have its path of movement during the travel of the typewriter carriage 25 intercepted by a key-operated decimal or counter-stop, and thereby said stop will arrest said carriage. These carriage stops may be mounted on a rack bar, in which they slide, and from which they are projected to where they will be intercepted by said counter-stops. For so projecting said carriage stops, a key may be arranged at the typewriter keyboard so as to move a setting arm, which arm is arranged to align 30 35 with different rack stops according to the position of the typewriter carriage, and said setting arm on the depression of said key, will project one of said rack stops. The rack bar which carries said stops may 40 45 embrace them so that the stops are held by internal teeth on said bar. This rack within which said stops lie, preferably comprises spring detents which are arranged to hold said stops in any position in which they 50 55 may be standing. Said detents may comprise spring pressed balls which are arranged to bear against the edge of said stops, and the springs cause said balls to enter notches therein. For returning any of the projected stops to ineffective position, there may be provided a cam member pivoted on the casing in which the key-operated stops are guided, and said cam member may be swung over said counter- 55 stops so as to lie in the path of the rack

stops and then the cam will return any projected rack stops. Any rack stop which does not lie in the path of said swinging cam at the time the cam is swung to operative position will be returned by the travel 60 of the carriage, which causes said stops to strike said cam and ride up on the surface of it.

The present invention provides a simple, effective and compact structure, which is 65 not likely to foul the work-sheet or prove otherwise objectionable.

Other features and advantages will hereinafter appear.

In the accompanying drawings, Figure 1 70 is a diagrammatic side view of a typewriting machine showing my invention applied thereto. Fig. 2 is a perspective view of some principal parts of my invention and some related parts. Fig. 3 is a plan view 75 of the same. Fig. 4 is a side elevation of a portion of the machine. Fig. 5 is a section through a rack bar.

In the Underwood typewriting machine, keys 1 depress levers 2 to swing bell cranks 80 3 so that type bars 4 swing upwardly and rearwardly, causing type 5 to print against a work-sheet on a platen 6. Said platen is mounted in a traveling carriage 7 which is drawn in letter-feeding direction by means of a spring barrel 8, and is controlled in said letter feed by means of an escapement wheel 9 carrying a ratchet wheel 10, which ratchet works in a rack 11 on said carriage. Said escapement wheel 9 is controlled by vibrating dogs 12 and 13, which are operated by means of a frame 14 forming an extension of a universal bar 16, which universal bar is operated by heels 17 on the type bars as they rise toward the carriage. In this way, 95 every time a key is depressed, the type 5 makes an impression on the carriage and the typewriter carriage is fed forward one letter space. In order to position said carriage at any desired letter space, a tabular mechanism is employed comprising key levers 18 pivoted at 19 which, when depressed, cause decimal stops or counter-stops, which may be in the form of plungers 20, resting on their rear ends, to be raised so that the 100 raised plunger will lie in the path of a stop 21 projecting from a rack bar 22 on the carriage 7, as seen in Fig. 1. Said rack bar is fast on the typewriter carriage and consequently when the stop 21 strikes the coun- 110

ter-stop 20, said carriage is arrested in its travel across the machine. Said carriage, by the depression of a key 18, is simultaneously released from the escapement dogs 12 and 13, so that it may be drawn freely in letter feeding direction by means of spring barrel 8. For this purpose, each counter-stop 20 when raised, is arranged to lift the rack 11 out of the ratchet wheel 10, and thus free the carriage 7 from the control of the dogs 12 and 13. This is accomplished by means of a universal bar 23 fast on a rock shaft 24, which carries a rock arm 25, and said universal bar is arranged every time any plunger 20 is raised, to be struck by a heel 26 on said plunger 20, and draw down a link 27 so that said link will swing bar 28 on its pivot 29 and lift the rack 11, swinging it on its pivoted arms 30. Said bar 28 is provided with a wheel 31 which is permitted to revolve idly as the rack bar 11 slides over so that said carriage will be drawn forward without resistance. The rack bar 22 in which the stops 21 are carried, is fast on the typewriter carriage, on which it is supported by arms 32, and said rack bar is built up of two rack bars facing each other, 33 and 34, which have teeth 35 facing each other, so that the stops 21 may rest between said teeth and be held firmly against movement longitudinally of the bar. Over the top of the bars 33 and 34 is a casing 35 comprising openings 36, through which the upper ends of the stops 21 project when said stops are in ineffective position in said rack bar. The upper ends of the rack stops 21 are somewhat smaller than the lower ends, having shoulders 37 which are arranged to strike against the projecting edges 36^a of the casing 35^a, and hold said stops against being withdrawn from above. In the reduced upper end of said stops 21 there is formed on at least one side, notches 38 in which spring pressed balls 39 are pressed by means of coil springs 40. Said springs 40 as seen in Figs. 3 and 5, lie in openings 41 in each of the rack bars 33 and 34, and are so arranged that the springs for adjacent stops are in openings in opposite rack bars. The casing 35^a is held on the rack bars 33 and 34 by means of screws 42, so that said united rack bars, with the stops in them form an easily handled unit.

The stops 21 are normally in ineffective position, as seen in Fig. 1. They are moved to effective position, as seen in Fig. 4, by means of a slide arm 43 which is operated by a key 44, and which on depression of said key is moved to dotted line position, seen in Fig. 4, carrying down with it the stop 21. Said stop 21 then will lie in the path of any counter-stop 20 which may be raised. The connections between the key 44 and the slide arm 43 include a rock arm 45 on which said slide arm 43 is pivoted at an enlarged open-

ing 43^a, (see Fig. 1); a rock shaft 46, on which said rock arm 45 is fast, and a rock arm 47 fast on the shaft 46, which arm 47 has a fork 48 which is arranged to underlie the lever 49 of key 44. Said slide arm 43 is normally drawn upward by means of a spring 50 which is anchored in a pin projecting from the casing 51 in which the counter-stops 20 are guided. The pin 52 by which the slide arm 43 is pivoted to the rock arm 45, forms a guide for said slide arm 43 at its lower end, while at its upper end said arm 43 rides in a slot 53 formed in a plate 54 on the upper end of said casing 51. The slide arm 43 has a U-shaped head and is located so that it alines at each letter space with one of the stops 21, and the stop which it is arranged to depress at any moment is the one which would lie against the extreme left hand counter-stop 20, as viewed in Fig. 2, if both the stop and counter-stop were in effective position.

In the structure herein shown, the counter-stops 20 form a decimal tabulator, and the left hand counter-stop 20, as seen in Fig. 2, will arrest the carriage at the units position in any column. The stop which the slide arm 43 will project at any moment is the one which, if the left-hand counter-stop is in operative position, will arrest the carriage at the printing point at which it is then standing. This is indicated on the scale 56 on the frame of the typewriter by the pointer 57 on the carriage.

For returning any projected stop 21 to ineffective position, there is provided a swinging cam 58 pivoted at 59 on the plunger frame 51, and arranged to be swung so that its cam face 60 will lie in the path of any projecting stop 21, as seen at Fig. 4, and return said stop to ineffective position. The cam face 60 is preferably symmetrically arranged so that the movement of the carriage in either direction will cause the stops to ride up over the cam and be returned to their ineffective position. The member 58 may comprise a handle 61 by which said member is swung into position. Said member is normally drawn out of its operative position by means of a spring 62 anchored to a pin 63 projecting from the frame 51, and said member carries a stop pin 64, which is arranged, as seen in Fig. 3, to bear against the casing 51 and prevent the member from being swung too far outward. As is best seen in Fig. 4, when the cams are in their effective positions, they over-lie the ends of the counter-stops 20, and the cam surface 60 is preferably tapered down so that when the member 58 is swung inwardly, its front edge will force upwardly into ineffective position any projected stop 21 which said edge may strike.

It will be noted that the counter-stops 20 are guided in slots 65 in the closed top of

casing 51, and that the stops 21 are equally firmly held closely adjacent thereto. This gives great accuracy of alinement and reduces the strain on the thin parts of the 5 mechanism.

Variations may be resorted to within the scope of the invention, and portions of the improvements may be used without others.

Having thus described my invention, I 10 claim:

1. In a typewriting machine, the combination with a rack bar, of a series of stops vertically slidable to effective and ineffective positions on said bar, an arm vertically slid- 15 able to slide said stops, means for guiding said arm, a rock shaft for drawing said arm, and a key arranged to swing said rock shaft.

2. In a typewriting machine, the combination with a rack and stops thereon, of a 20 stop setting key, a rock arm operated thereby, and a vertically slidable stop setting member moved by said rock arm and having a U-shaped extension overhanging the stops and moved downwardly when the key is de- 25 pressed to set a stop.

3. In a typewriting machine, the combination with a rack and stops thereon, of a stop setting key at the keyboard, a rock shaft adjacent the base of the machine swung 30 by said key, a rock arm on said shaft, a stop setting member extending from said rock arm to a point over said stops, and a guide adjacent said rack in which said setting member is vertically slidable downwardly 35 to project the stops downwardly from the rack.

4. In a typewriting machine, the combination with a traveling carriage, of stops on said carriage, stops on the main frame of 40 said machine, a casing for each set of stops set so that said casings pass close to each other, the stops being normally within said casings and supported at the surface thereof, a key for projecting said stops to arrest 45 said carriage, and a restoring cam for returning the projected stops on the carriage, said key operable to advance said cam between the casings, said cam formed to return any stops in its path during said advance.

5. In a typewriting machine, the combination of a carriage, a set of vertically slidable stops carried thereby, an operating member movable vertically to selectively operate said stops, a machine frame, stops carried there- 55 by, and means to selectively operate said last named stops into position to coöperate with the first named stops.

6. In a typewriting machine, the combination of a carriage, a series of vertically slid- 60 able stops carried thereby, a stationary support, and a vertically slidable member mounted therein in position to operate said stops.

7. In a typewriting machine, the combina- 65 tion with plunger stops, of a frame in which

said stops are supported and guided, a type- writer carriage, vertically movable stops car- 70 ried thereby in position to travel adjacent said plunger stops, a device to selectively set the carriage stops, and a re-setting device movable into a position between the plunger stops and carriage stops for returning the latter to ineffective position.

8. In a typewriting machine, the combina- 75 tion with a carriage, of vertically movable stops carried thereby, means to set said stops, and a returning cam movable horizontally into a stop-returning position, said cam formed to return the stops that lie in its path during said movement, and to cause the remaining set stops to be returned by the movement of the carriage.

9. In a typewriting machine, the combina- 80 tion with a carriage, of a series of vertically movable stops carried thereby and arranged 85 in a line extending in the direction of the travel of the carriage, a vertically movable stop-setting device comprising a vertical arm in front of said stops and a part extending rearwardly over the stops, and stationary 90 means to guide said device in its vertical movement.

10. In a typewriting machine, the combina- 95 tion with vertically slidable stops and a casing within which they normally lie, of a rack bar fast on the typewriter carriage, stops on said rack bar arranged to travel adjacent said casing, a vertically slidable setting device for selectively moving said rack stops downwardly to set position, and a cam 100 arranged to be swung over said first-named stops and into the path of said set rack stops for returning said stops to ineffective position.

11. In a typewriting machine, the combi- 105 nation with a rack bar and stops slidable thereon to a projected position, of an arm movable at right angles to the sliding move- ment of said stops, said arm having a cam surface for moving projected stops that lie 110 in its path as said arm swings toward them, and said surface formed for returning the remaining projected stops as they travel across said surface.

12. In a typewriting machine, the combi- 115 nation with stops movable vertically to op- erative position, of a horizontally moving cam formed to return the stops to inopera- tive position during said movement of the cam, and a key for moving said stops.

13. In a typewriting machine, the combi- 120 nation with a casing and vertically slidable stops therein, of a casing and rack stops movable therein closely adjacent said first casing, and a key-operated stop-projecting slide overhanging the rack stops and slidable vertically downward for projecting said rack stops vertically downward from their casing.

14. In a typewriting machine, the combi- 125 nation with a carriage, of a series of verti-

callably movable stops carried thereby, a machine frame, a series of counter-stops mounted therein and slidable vertically into position to coöperate with the first-named stops, 5 selective means for operating the counter-stops, and a vertically-slidable stop-setting device overhanging the stops on the carriage, said stops selectively brought by the travel of the carriage into position to be set by said 10 device into position to be engaged by the counter-stops.

15. In a typewriting machine, the combination of a carriage, a set of vertically mov-

able stops thereon, a machine frame, a set of vertically slidable stops therein, and a key- 15 operated stop-setting device to selectively set the stops on the carriage into position to coöperate with an operated stop on the machine frame, said stop-setting device comprising an arm slidable up and down on the 20 machine frame and having a projection overhanging the stops on the carriage.
